UNITED STATES PATENT OFFICE.

WILLIAM PETERSEN, OF TRAER, IOWA.

COMBINATION CHICKEN COOP, NEST, BROODER, AND HATCHERY.

Application filed April 24, 1925. Serial No. 25,503.

The purpose of my invention is to provide a combination chicken coop, nest, brooder and hatchery of comparatively durable, simple and inexpensive construction.

More particularly, it is my purpose to provide a device of the general class under consideration having a number of novel features of structure.

One purpose of my invention is to provide such a device, which can be readily constructed in batteries of compartments.

Another purpose is to provide such a device having a series of compartments provided in each case with partition members of peculiar construction, whereby each compartment may be divided into smaller compartments.

One of my particular purposes is to provide a novel means for supporting and operating said last-mentioned partition members.

Another purpose is to provide in such a device means for automatically regulating the heat and ventilation in the device.

Still another purpose is to provide in such a device partition members, which are readily interchanged or removed.

It is another purpose to provide in such a battery of such devices a series of partition members arranged on the same operating device, so that they may be simultaneously actuated.

Another purpose is to provide a device having a removable nest wall of novel construction.

With these and other objects in view, my invention consists in the construction, arrangement and combination of the various parts of my combination chicken coop, nest, brooder and hatchery, whereby the objects contemplated are attained, as hereinafter more fully set forth, pointed out in my claims, and illustrated in the accompanying drawings, in which:

Figure 1 shows a perspective view, parts being broken away and parts being shown in section of a device embodying my invention.

Figure 2 is a vertical, sectional view taken on the line 2—2 of Figure 1.

Figure 3 is a detailed, sectional view taken on the line 3—3 of Figure 1.

Figure 4 is another detailed, sectional view taken on the line 4—4 of Figure 1.

Figure 5 is a sectional view taken on the line 5—5 of Figure 2.

Figure 6 is a sectional view taken on the line 6—6 of Figure 1.

Figure 7 is a perspective view of one of the food and water troughs; and

Figure 8 is a sectional view through the lamp or heater casing.

Figure 9 is a detail sectional view showing the manner of mounting the doors.

Figure 10 is an enlarged detail view showing a partition fastening.

My improved device comprises a casing, which is provided with the end walls indicated in the accompanying drawings by the reference numeral 10, the rear wall 11, the inclined top member 12, the hinged top member 13, and the bottom member 14 terminating rearwardly from the front of the end walls 10.

At the front upper part of the casing forwardly of the hinged cover member 13, a tubular shaft 15 extends across the casing from end wall to end wall thereof.

For dividing the casing into a battery of compartments, I provide a series of walls extending from front to rear in parallel spaced relation and indicated generally by the reference character 16. The shaft 15 is extended through and helps to support and is supported by the walls 16.

Beneath the bottom 14 near the front and rear thereof are supporting feet or the like 17 for holding the bottom 14 slightly spaced above the ground.

The portions of the end walls 10 forwardly of the bottom 14 extend downwardly flush with the lower surfaces of the feet 17.

The end walls and the walls 16 divide the entire casing into a series of compartments indicated generally at A, B, C and D.

Each of said compartments is divided into a series of smaller compartments by means of detachably mounted partition elements. These partition elements are mounted on shafts like the shaft 15.

Rearwardly of the shaft 15 and below the forward part of the hinged cover member 13 is a shaft 19 similar to the shaft 15 and substantially spaced rearwardly from the shaft 19 is mounted another shaft 20 similar to the shafts 15 and 19.

Each of the shafts mentioned has a series

of pairs of opposite holes 21 (see for instance Figure 9), the holes being aligned lengthwise of the shaft.

I provide the removable partition elements above mentioned. These may comprise a frame 22 supporting a screen element 23 and having at its upper part spaced hook members 24, the ends of which are designed to project through the pairs of holes 21 for thus supporting the partition element on one of the shafts 15, 19 or 20.

These partition elements may be of the type mentioned comprising a frame screen, or they may consist of a slotted piece of sheet metal 25 as shown at the right-hand part of Figure 1, or an imperforate sheet of metal 26, as illustrated in Figure 2.

At the upper edge of each partition element is a projecting flange 27, which may be grasped for lifting the partition member for pulling the hooks out of the holes 21 and detaching the partition member from its shaft.

I usually use the imperforate type of partition member 26 on the shaft 19, because these partition members may be swung upwardly as shown in Figures 1 and 2 to form top members for the front portion of the compartments A, B, C and D.

When the partition members are mounted on all of the shafts, it will be seen that each of the compartments A, B, C and D is divided into three smaller compartments, which for convenience, I call the hatching or nest compartment 28, the brooder compartment 29 and the run compartment 30.

Incidentally the walls 16 between the various run compartments may be provided with openings 31 provided with screen 32 if desired.

On each partition element, there is provided a pair of projecting L-shaped members 33. (See Figures 1 and 2). Channel-shaped troughs 34 of the kind shown for instance in Figure 7 are provided with upwardly projecting end walls 35. One end of each trough is provided with a hole 36 and the other end with a slot 37 for receiving the members 33 for hanging the trough on the partition member detachably.

The shafts 15, 19 and 20 project through one of the end walls 10, as shown for instance in Figure 1, and have on their outer ends crank arms 38 of somewhat resilient material adapted to coact with projections or the like 39 on the end wall 10 (see Figures 1 and 6).

By manipulating the crank arms 38, all of the partition members in one row may be simultaneously swung as the shaft on which they are hung rotates. The coaction of the crank arm 38 and the projections 39 make it possible to hold the partition elements thus moved in any desired position of their adjustment.

Thus it is possible to swing the partition members 26 on the shafts 19 upwardly and forwardly until they stand in position illustrated in Figures 1 and 2 for serving as covers or tops for the run compartments 30. 70

The front part of each nest and hatching compartment 28 has the walls 10 and 16 or walls 16 as the case may be, provided with spring clips 40, as shown in Figures 2 and 5. Nest walls 41 are provided with rolled 75 ears 42 in each end to receive wires 43 and 10. The clips 40 are of spring material and when the partition 41 is put in place the wires 43 spring them to the dotted line position. After the wires 43 are in 80 place the clips 40 spring back thereby securely holding the partition in place.

By pushing the nest wall 41 rearwardly, it can be detached from the clips and then lifted out for convenience in cleaning or for 85 connecting together the compartments 28 and 29 or as may otherwise be desired.

The hinged top member 13 is provided at its ends and front portion with downwardly projecting screen flanges 44. The flange 44 90 is provided with reinforced slots or notches 45 to receive the upper edges of the walls 16. The central portion of the top of the device is raised somewhat to allow access to the shaft 20 and access to the shaft 19 is had 95 by raising the hinged cover member 13. These screen flanges 44 permit some raising of the hinged top member 13 for permitting ventilation without exposing chicks to danger from rats and the like. 100

Seated in one of the walls 16 below the hinged top member 13 is an expansible thermostat device 46, for engaging and raising the top member 13 when the temperature in the casing rises beyond a certain degree. 105

Extending across the device near the top of the compartment 28 is a flat tubular heat pipe 47, which projects through both end walls 10. At one end of the casing, the heat pipe 47 communicates with a lamp casing or the like 48. The bottom of the lamp casing 48 is opened, except for a plate 49 of considerably less diameter than the lamp casing. The plate 49 has a bar 50 or the like extending from one side thereof and hinged 110 to the wall of the casing 48 as at 51.

Extending from the other side of the plate 49 is a rod 52 with which a swinging hook 53 on the wall of the casing 48 coacts. A lamp 54 may be supported on the plate 120 49 and may be released and taken out by being grasped and lifted from the plate 49, after which the hook 53 may be released, whereupon the plate 49 will drop down, permitting the removal of the lamp. 125

At the opposite end of the main casing from the lamp casing 48, the heat pipe 47 extends downwardly to the bottom 14, beneath which it extends again across the main casing to the end where the casing 48 is lo- 130

cated and thence upwardly to the chimney 54. A device of this kind has a number of advantages and is capable of a great variety of uses.

5 The compartment 28 may be used for a hatching or nest compartment with the wall 41 forming the front wall of the nest. The compartment 41 and the rear partition element may be removed for throwing the 10 compartments 28 and 29 together, if desired.

The compartment 29 may be formed as a brooder compartment or as a feeding compartment for a hen. If the hens are in the nest compartments, the shaft 20 may be rotated for raising the rearward partition elements from the position shown in full lines in Figure 2 to the dotted line position shown in that Figure, whereupon the hens may go into the compartment 29.

20 When the partition elements are then swung down again, the hens will be urged back into the next compartment. The front compartments 30 from runs where the chicks can sun themselves and be on the grass.

25 By using the screen or slotted partition elements on the shaft 19, the partition elements which form the tops for the compartments 30 will let the sun through, as may be desired.

30 It is, of course, understood that various types of partition elements are interchangeable, so that any type may be used on any of the shafts. Heat is furnished to the device by radiation when desired by lighting 35 the lamp 54. If the heat becomes too great in the device, the thermostat member 46 will raise the movable top 13 for allowing freer ventilation.

The entire device is rat proof and this is 40 true, even when the hinged cover member 13 is raised somewhat.

The devices are easily portable and can be moved about a chicken yard, so as to let the chicks have access to fresh grass every 45 day or several times a day. It will be seen that the entire device is easily cleaned.

Any number of units may be used in a battery.

The device may be used for hatching 50 chicks and as a brooder and run. It may be used as a brooder and run for incubator chickens.

It may be seen that different hatchings of 55 chickens may be kept in the different compartments A, B and so forth.

Numerous changes may be made in the details of the construction and arrangement of the parts of the device without departing from the real spirit and purpose of my invention, and it is my intention to cover by 60 my claims any modified forms of structure or use of mechanical equivalents, which may be reasonably included within their scope.

I claim as my invention:

65 1. In a device of the class described, a

casing, a tubular shaft supported therein provided with transverse holes arranged in opposite pairs, a partition element having hook members received in the pairs of said holes.

2. In a device of the class described, a casing, a tubular shaft extending across the upper part of the casing provided with holes in its wall arranged in opposite pairs, a partition element having hook members each 70 received in a pair of said holes and adapted to be freely lifted therefrom.

3. In a device of the class described, a casing, a tubular shaft extending across the upper part of the casing provided with holes 80 in its wall arranged in opposite pairs, a partition element having hook members each received in a pair of said holes and adapted to be freely lifted therefrom, and means for rotating the tubular shaft.

4. In a device of the class described, a casing, a tubular shaft extending across the upper part of the casing provided with holes in its wall arranged in opposite pairs, a partition element having hook members each 90 received in a pair of said holes and adapted to be freely lifted therefrom, and means for rotating the tubular shaft and for holding it in different positions of its rotation.

5. In a device of the class described, a 95 casing, a tubular shaft extending across the upper part of the casing provided with holes in its wall arranged in opposite pairs, a partition element having hook members each received in a pair of said holes and adapted 100 to be freely lifted therefrom, and means outside the casing for rotating the tubular shaft and for holding it in different positions of its rotation.

6. In a device of the class described, a 105 casing, a tubular shaft extending across the upper part of the casing provided with holes in its wall arranged in opposite pairs, a partition element having hook members each received in a pair of said holes and adapted 110 to be freely lifted therefrom, a hinged cover member, adapted when in closed position to overlie the shaft, and when in open position to permit the hooks to be lifted from the holes for removing the partition element.

7. In a device of the class described, a 115 casing, a series of parallel partitions therein for forming a battery of compartments, a tubular shaft arranged transversely of the compartments thus formed, partition elements in the various compartments detachably but non-rotatably hung on said shaft.

8. In a device of the class described, a 125 casing, a series of parallel partitions therein for forming a battery of compartments, a tubular shaft arranged transversely of the compartments thus formed, partition elements in the various compartments detachably but non-rotatably hung on said shaft,

and means outside the casing for rotating the shaft and thus simultaneously moving all of said elements.

9. In a device of the class described, a casing, a series of parallel partitions therein for forming a battery of compartments, a tubular shaft arranged transversely of the compartments thus formed, partition elements in the various compartments detachably but non-rotatably hung on said shaft, and means for rotating said shaft and holding it in various positions of its rotation.

10. In a device of the class described, a casing, partition elements hingedly mounted

in the casing, L-shaped members mounted on the partition elements and troughs having their ends detachably supported on the L-shaped members.

11. In a device of the class described, a casing having end walls, a heater pipe extending through the end walls of said casing, a heater element supported on said pipe outside the main casing, said pipe, after passing through said casing, extends down and returns under the floor of said casing and then extends upward and terminates at a point above said heating element. 20 25

WILLIAM PETERSEN.
